P. H. Kells,
Monter.

Nº 10671.

Patented Mar. 21, 1854.

UNITED STATES PATENT OFFICE.

PHILIP H. KELLS, OF HUDSON, NEW YORK.

IMPROVEMENT IN HARVESTERS.

Specification forming part of Letters Patent No. **10,671**, dated March 21, 1854.

To all whom it may concern:

Be it known that I, PHILIP H. KELLS, of Hudson, in the county of Columbia and State of New York, have invented a new and useful Improvement in Mowing-Machines; and I do hereby declare that the following is a full, clear, and exact description of the construction and operation of the same, reference being had to the annexed drawings, forming part of this specification, in which—

Figure 1 is a side elevation of the machine. Fig. 2 is a plan of the same.

Similar letters of reference in the several figures indicate the same part of the machine.

The object of this invention is to give the cutter-bar of my machine such a position as will cause the cutter or knife to conform to the surface of the ground passed over, and prevent injury to the cutting-teeth when the machine is running over water-furrows or other broken ground.

The invention consists in so placing the knife-frame that the bar to which the cutting-blade is attached shall be in a range with and perpendicular to the side of the guiding-roller when the axis of that roller is parallel to the axis of the driving-wheel.

To enable others skilled in the art to make and use my invention, I will proceed to describe its construction and operation.

In the drawings, A is the driving-wheel, having on its side face the cogs *a*, into which meshes the pinion *B* on the shaft *C*. On the rear extremity of the shaft *C* is the wheel *b*, meshing into the wheel *c* on the shaft *D*, which carries on its fore extremity the eccentric *d*, to which, by the band *e*, is attached the rod *f*, connecting the eccentric with the cutter-bar *n*. This arrangement, which is not arbitrary, may be replaced by any equivalent mechanical device.

E is the guiding-roller, placed directly in front of the driving-wheel, and pivoted to facilitate the turning of the machine. The draft-bar *F* is in front of the roller, and the line of draft in the prolongation of the wheel and roller.

The knife-frame *H* is on the gearing side of the machine, and is attached to the gear-frame *I* by the brace *h*. To this frame are attached the guard-teeth *i*, through which reciprocates the bar *n*, carrying the knife *m*, said bar being connected with the rod *f* by the joint *l*. The

knife-frame *H* is placed in advance of the driving-wheel *A*, and is so situated that the bar *n*, which holds the cutter *m*, shall always range with the roller *E* and be perpendicular to its side when the axis of the said roller is parallel to the axis of the driving-wheel, for objects which will be hereinafter set forth.

The operation of my machine is as follows: The forward motion of the driving-wheel *A* produces a reciprocating motion of the knife *m* under the frame *H* and in the slots of the teeth *i* by reason of the connecting-rod *f*, eccentric *d*, shafts *C* and *D*, pinion *B*, cogs *a*, and cog-wheels *b* and *c*. The placing of the cutter-bar *n* so as to range with the roller *E* when its axis is parallel to the axis of the driving-wheel enables the machine to operate with perfect regularity, notwithstanding the uneven surface upon which it is worked, as the cutter-bar will always run the same distance from the surface of the ground, its vertical movements being so governed by the guiding-pulley as to have the same rise and fall as that pulley at the same time. This is of great importance, as any position other than that here given would interfere materially with the operation of the cutters when running across water-furrows and other inequalities, for when the pulley would be in the trough of the furrow the cutters would be thrust into its forward side and be broken or bent in the rise of the machine, whereas in my machine the bar *n* will in that case be at the constant distance from the bottom of the furrow, and, rising with the revolution of the pulley, will preserve the same distance from the surface of the ground and carry the cutters clear of the sides of the furrow. The same results would obtain if the bar *n* was placed without and to the rear of the above-specified range, as the distance between the bar and the surface of the ground would necessarily be variable, and the teeth therefore liable to a variety of accidents.

It is unnecessary to enlarge upon the advantages of the above-specified position of the cutter-bar, as the smoothness of cutting which it insures and the prevention of accidents which it effects are of themselves sufficient to demonstrate its utility.

What I claim as my invention, and desire to secure by Letters Patent, is—

Laying the bar *n*, which carries the cutting-

teeth, ranging with the guide-roller and perpendicular to its side face when the axis of said roller is parallel to the axis of the driving-wheel, for causing the cutter-bar to conform to the surface of the ground passed over, and for the prevention of accidents to the cutting teeth, as herein fully set forth, said bar being on the gearing side of the machine.

In testimony whereof I have hereunto signed my name before two subscribing witnesses.

PHILIP H. KELLS.
